WEB PERFECTING ROTARY PRINTING
PRESS

Howard M. Barber, Pawcatuck, Conn., assignor
to C. B. Cottrell & Sons Company, Westerly,
R. I., a corporation of Delaware

Application February 3, 1936, Serial No. 62,071

16 Claims. (Cl. 101—178)

In high speed web perfecting rotary printing presses where quick drying inks and ink drying units are employed in connection with the web printing units, it is most important that the several units be so located with respect to one another as to produce the best possible results with a minimum amount of space and a minimum travel of the web.

This invention comprises, generally, two printing units and one or two drying units and means for passing the web through said printing and drying units.

This invention more specifically comprises two printing units arranged one above the other and two drying units, one offset from and located at right angles to one of the printing units and the other being located in line with the press beyond the other printing unit.

Practical embodiments of my invention are represented in the accompanying drawings, in which—

Fig. 1 represents a diagrammatic top plan view of a double two color press embodying my invention, the means for removing the vapors rising from the heating cylinders of the drying units being omitted;

Fig. 2 represents a diagrammatic front end view of the press; and

Fig. 3 represents a diagrammatic longitudinal vertical section, taken in the plane of the line III—III of Fig. 1, looking in the direction of the arrows.

The first printing unit is herein shown as adapted to print in two colors, the impression cylinder being denoted by 1, the form cylinders by 2, 3 and their inking mechanisms by 4, 5.

The second printing unit for perfecting the web is located above the first printing unit and it is herein shown as adapted for printing in two colors, the impression cylinder being denoted by 6, the form cylinders by 7, 8 and their inking mechanisms by 9, 10.

The first drying unit is herein shown as comprising a large heating cylinder 11 and two small cooling cylinders 12, 13. A pipe 14 serves to introduce a heating medium, as steam, into the cylinder 11; and pipes 15, 16 serve to introduce a cooling medium, as water, into the cylinders 12, 13 respectively. This drying unit is offset from 50 and located at right angles to the press.

The second drying unit is herein shown as comprising a large heating cylinder 17 and two small cooling cylinders 18, 19. A pipe 20 serves to introduce a heating medium, as steam, into the cylinder 17; and pipes 21, 22 serve to introduce a cooling medium, as water, into the cylinders 18, 19 respectively. This drying unit is located in line with the press sufficiently beyond the second printing unit to eliminate the deleterious effects of the heat from the heating cylinder 17

on the inking mechanism 10 of the form cylinder 8 of the second printing unit.

A turning bar 23 is provided in position to direct the web laterally from the first printing unit to the first or offset drying unit, and a second turning bar 24 is located in position to lead the web back into alignment with the press before the web is passed to the second or perfecting printing unit.

The web may be led through the press as follows:

The unprinted web passes from the web supply roll 25 around guide rolls 26, 27, 28, 29 to and around the impression cylinder 1 of the first printing unit. From thence the web passes 15 around the turning bar 23 and guide roll 30 to and around the heating cylinder 11 of the first drying unit. From thence the web passes around the cooling cylinder 12, guide roll 31, cooling cylinder 13 and guide rolls 32, 33, 34* to the 20 turning bar 24 for bringing the web back into line with the press.

The web then passes around the guide roll 35 and in engagement with the compensating roll 36 to and around the impression cylinder 6 of the 25 second or perfecting printing unit located over the impression cylinder 1 of the first printing unit. The web then passes over guide rolls 37, 38 to and around the heating cylinder 17 of the second drying unit located in line with the press 30 beyond the second printing unit. The web then passes around the cooling cylinder 18, guide roll 39, cooling cylinder 19 and guide rolls 40, 41, 42 downwardly to a predetermined point for further operations, as cutting, folding, stacking, etc.

The heating cylinders of the two drying units may be provided with suitable means for removing the vapors which arise from the inks as the web passes around said heating cylinders. In the present instance I have shown blowers 43, 44 with their hoods 45, 46 partially enclosing the heating cylinders 11, 17 respectively, and the exhaust pipes 47, 48.

It will be understood that the printing units may be driven by well known or approved means, not shown herein, and that the path of the web may be varied to suit different requirements.

It will also be seen that the path of the web is such that the freshly printed side of the web, after it is dried by each drying unit, will not 50 be again subjected to the heat rising from the heating cylinder of said unit.

It will also be seen that I have provided an arrangement of the several units whereby the inks on the freshly printed sides of the web may be 55 thoroughly dried with a minimum travel of the web, the form cylinders and their inking mechanisms of the two printing units being so positioned that ready access thereto is obtained.

It is evident that various changes may be re- 60

sorted to in the construction, form and arrangement of the several parts without departing from the spirit and scope of my invention, and hence I do not intend to be limited to the particular embodiments herein shown and described, but

5 What I claim is:

1. In a web perfecting rotary printing press, first and second printing units in line with the press, a drying unit comprising heating and cooling cylinders located out of line with the press, and means for passing the web through said printing and drying units. 10
2. In a web perfecting rotary printing press, first and second printing units in line with the press, a drying unit comprising heating and cooling cylinders located out of line with the press at right angles thereto, and means for passing the web through said printing and drying units. 15
3. In a web perfecting rotary printing press, first and second printing units in line with the press, a drying unit comprising heating and cooling cylinders located out of line with the press, and means for passing the web successively through the said first printing unit, the drying 20 unit and the second printing unit. 25
4. In a web perfecting rotary printing press, first and second printing units in line with the press, a drying unit comprising heating and cooling cylinders located out of line with the press at right angles thereto, and means for passing the web successively through the said first printing unit, the drying unit and the second printing unit. 30
5. In a web perfecting rotary printing press, first and second printing units in line with the press, two drying units, one comprising heating and cooling cylinders located out of line with the press and the other comprising heating and cooling cylinders located in line with the press beyond the second printing unit, and means for passing the web through the said printing and drying units. 35
6. In a web perfecting rotary printing press, first and second printing units in line with the press, two drying units, one comprising heating and cooling cylinders located out of line with the press at right angles thereto and the other comprising heating and cooling cylinders located in line with the press beyond the second printing unit, and means for passing the web through said printing and drying units. 40
7. In a web perfecting rotary printing press, first and second printing units in line with the press, two drying units, one comprising heating and cooling cylinders located out of line with the press and the other comprising heating and cooling cylinders located in line with the press beyond the second printing unit, and means for passing the web through said printing and drying units. 45
8. In a web perfecting rotary printing press, first and second printing units in line with the press, two drying units, one comprising heating and cooling cylinders located out of line with the press at right angles thereto and the other comprising heating and cooling cylinders located in line with the press beyond the second printing unit, and means for passing the web through said printing and drying units. 50
9. In a web perfecting rotary printing press, first and second printing units in line with the press, a drying unit comprising heating and cool- 55

ing cylinders located out of line with the press, and means for passing the web through said printing and drying units, said means including turning bars around which the web is led on its way to and from the drying unit. 60

10. In a web perfecting rotary printing press, first and second printing units in line with the press, a drying unit comprising heating and cooling cylinders located out of line with the press at right angles thereto, and means for passing the web through said printing and drying units, said means including turning bars around which the web is led on its way to and from the drying unit. 10

11. In a web perfecting rotary printing press, first and second printing units in line with the press, two drying units, one comprising heating and cooling cylinders located out of line with the press and the other comprising heating and cooling cylinders located in line with the press beyond the second printing unit, and means for passing the web through the said printing and drying units, said means including turning bars around which the web is led on its way to and from the offset drying unit. 15

20

12. In a web perfecting rotary printing press, first and second printing units in line with the press, two drying units, one comprising heating and cooling cylinders located out of line with the press at right angles thereto to one of the printing units and the other comprising heating and cooling cylinders located in line with the press beyond the second printing unit, and means for passing the web through said printing and drying units, said means including turning bars around which the web is led on its way to and from the offset drying unit. 25

30

13. In a web perfecting rotary printing press, first and second printing units arranged one above the other in line with the press, a drying unit comprising heating and cooling cylinders located out of line with the press, and means for passing the web through said printing and drying units. 35

40

14. In a web perfecting rotary printing press, first and second printing units arranged one above the other in line with the press, a drying unit comprising heating and cooling cylinders located out of line with the press at right angles thereto, and means for passing the web through said printing and drying units. 45

45

15. In a web perfecting rotary printing press, first and second printing units arranged one above the other in line with the press, two drying units, one comprising heating and cooling cylinders located out of line with the press and the other comprising heating and cooling cylinders located in line with the press beyond the second printing unit, and means for passing the web through the said printing and drying units. 55

55

16. In a web perfecting rotary printing press, first and second printing units arranged one above the other in line with the press, two drying units, one comprising heating and cooling cylinders located out of line with the press at right angles thereto and the other comprising heating and cooling cylinders located in line with the press beyond the second printing unit, and means for passing the web through said printing and drying units. 65
